CASE

Irving Hill and George L. Miller, Lawrence, Kans.,
assignors to The Lawrence Paper Company,
Lawrence, Kans., a corporation of Kansas

Application January 16, 1950, Serial No. 138,770

3 Claims. (Cl. 229—39)

1

This invention relates to cases formed of corrugated, solid fiber or similar stiff board and has for its principal object to provide a case of this character with top and bottom flaps having interlocks that are formed as parts of the flaps and which are easily manipulated and which securely retain the flaps in closed position.

Other objects of the invention are to provide flap interlocks for such cases wherein the interlocks are entirely within the boundaries of the flaps so that no additional material is required in constructing the case; to provide interlocks having no protruding parts that make uneven bearing surfaces for the case; to provide interlocks that do not require supplemental fastening means such as tape or stitching; to provide flap interlocks which have their interlocking efficiency enhanced by the contents to be placed in the case; and to provide interlocks that are readily released when opening up the cases and for collapsing the cases when the cases are to be stored or shipped for reuse.

Further objects of the invention are to provide an interlock for the flaps of a stiff board case including a specially scored corner on one flap adapted for insertion through bias slot-like openings in the underlying flap and to provide a skid element for guiding the corner into locking position.

In accomplishing these and other objects of the invention hereinafter pointed out, we have provided improved structure, the preferred forms of which are illustrated in the accompanying drawings wherein:

Fig. 1 is a perspective view of a case having top and bottom flaps equipped with interlocks embodying features of the present invention.

Fig. 2 is a perspective view of the case showing the top flaps in open position and parts of the case broken away to better illustrate the interlocks of the bottom flaps.

Fig. 3 is an enlarged fragmentary perspective view of one end of the case particularly illustrating the position of the flaps prior to engagement of the interlocks.

Fig. 4 is a similar view showing the interlocks moving into position to lock the flaps together.

Fig. 5 is a plane view of the blank from which the case is formed.

Fig. 6 is a section on the line 6—6 of Fig. 4 illustrating entrance of one of the corner locks into the slot of an underlying flap, the corner lock being shown as guided into position by means of a skid tab.

Fig. 7 is a similar section after the flaps are in interlocked position.

2

Fig. 8 is an enlarged perspective view similar to Figs. 3 and 4 but showing the flaps in interlocked relation.

Fig. 9 is a section on the line 9—9 of Fig. 8 to illustrate the tongue and slot engagement of the interlocking portions of the flaps.

Fig. 10 shows a modification of the invention wherein the corner tabs fold back instead of being pushed forward.

10 Referring more in detail to the drawings:

1 designates a case formed of corrugated solid fiber or similar stiff board material and having top and bottom flaps equipped with interlocking features in accordance with the present invention 15 whereby the case is adapted for shipping eggs and other merchandise involving reuse of the case and opening for inspection.

The case is formed of a substantially rectangular sheet 2 having longitudinally spaced scores 20 3 and 4 inset inwardly of the longitudinal side edges 5 and 6 of the sheet and transverse scores 7, 8 and 9 registering with slits 10, 11, 12, 13, 14 and 15 that extend inwardly from the outer edges to the scores 3 and 4. The end adjacent 25 the score 9 has a projecting portion 16 that is offset outwardly intermediate the scores 3 and 4 and which is provided with a transverse score 17 that registers with the end edges 18 and 19 which continue outwardly from the scores 3 and 4. The scores thus define substantially elongated rectangular areas 20 and 21 and relatively shorter areas 22 and 23 which constitute respectively the sides 24—25 and ends 26—27 of the case illustrated in Fig. 1 when the blank is folded 30 on the scores 7, 8, 9 and 17 to bring the extension 16 into engagement with the corresponding portion at the opposite end of the blank as later described. The portions of the blank on the outer side of the score 4 and intermediate the slits 35 therein constitute longitudinal bottom flaps 28 and 29 and end bottom flaps 30 and 31 while the portions at the opposite side constitute top longitudinal flaps 32 and 33 and top end flaps 34 and 35. The ends 22 and 23 may 40 be provided below the score 3 with handhold openings 36.

The structure of the blank thus far described is conventional and conforms to the construction of that for the usual case. The bottom and 45 top closure flaps, however, are formed to have interlocks as now to be described.

The bottom closure flaps may overlap each other in various arrangements. For example, the longitudinal bottom flaps may overlap the end flaps as shown, the end flaps may overlap the longitudinal flaps, or the end flaps overlap one

of the longitudinal bottom flaps and underlie the other longitudinal bottom flap. The top closure flaps may be similarly arranged, however, the drawings show the end flaps as being adapted to overlie the longitudinal flaps. In any event, the corner of each overlying flap is provided with corner tabs adapted to engage bias-arranged slots in the underlying flap to form interlocks by which the flaps are secured together when in closed relation.

For example, the bottom flaps 28 and 29 have the corners thereof traversed by spaced scores 37 and 38 that converge slightly from the outer edges 6 toward the end edges forming one side of the slits 13, 14, 15 and the end edge 19 to provide triangularly shaped tabs 39 which are adapted to be offset from the plane of the longitudinal flaps by offsets 40 that are formed by bending on the converging scores 37 and 38. The underlying flaps which in the illustrated instance are the bottom end flaps 30 and 31 have slots 42 and 43 biasly arranged therein on angles conforming to the angularity of the innermost scores 38 and which correspond in length therewith so that when the flaps having the corner tabs are folded over the end flaps having the slots, the scores 38 will substantially register with the slots. The slots 42 and 43 have mid portions 44 of sufficient width to pass freely the thickness of the corner tabs when the corner tabs are passed therethrough as later described. The ends 45 and 46 of the slots, however, are relatively narrower than the thickness of the corner tabs so that the ends of the slots bind the ends of the offsets intermediate the scores 37 and 38 as indicated at 47 and 48 when these portions of the corner tabs are pushed through the slots.

In order to resist retractive movement of the tabs in the slots, tongues 49 may be provided intermediate the ends of the slots which are adapted to engage in slots 50 that are provided in corresponding relation within the offsets 40. Since the locking slots for both longitudinal flaps are located in the end flaps, one of the slots, for example, the slot 43 is of shorter length so as to leave ample amount of material therebetween and prevent unnecessary weakening of the material intermediate the slots. If desired, the top or bottom edges of the slot may be crushed or made thinner to facilitate entrance of the corner tabs as later described. While the drawing shows the slots and scores for the interlocks as being arranged at about 90°, it is obvious that the angles may be changed either way to facilitate the lock on various sizes and shapes of cases.

In the illustrated form of top closure, the top end flaps are provided with the angularly arranged spaced scores 51 and 52 to provide lock tabs 53 and 54 and the underlying ends of the longitudinal flaps 32 and 33 are provided with the angularly arranged slots 55 and 56 corresponding with the interlocking tabs and slots previously described in connection with the bottom flaps. The scores 51 and 52 extend from the outer edges 5 of the flaps and converge toward the end edges of the end flaps. The slots 55 and 56 are arranged in corresponding relation on the underlying longitudinal flaps and have relatively wide intermediate portions and narrower ends 57 and 58 conforming to the corresponding portions of the slots in the bottom flaps. Extending into the slots are tongues 59 which engage in openings 60 that are provided in the offsets 61 so that when the corner tabs

are inserted through the slots and the ends of the offsets 61 engage in the restricted ends 57 and 58 of the slots, the tongues 59 will slip into the openings 60.

5 In order to facilitate entrance of the corner flaps when the case has been packed, the longitudinal side flaps have tongues 62 that are formed in the corners of the flaps by substantially U-shaped slits 63, the terminals of the slits terminating short of the slots to provide ample material to prevent breaking through of the material. These tongues are subsequently folded retractively to underlie the slots and provide skids which direct the corner flaps as later described.

15 The blank thus described is folded on the score 8 to bring the side edge 64 of the portion 22 into registry with the score 17 and into engagement with the flange portion 16 so that it may be secured by a series of metal staples or stitching as indicated at 65 to thereby connect the end wall with the adjacent side wall. The blank may then be formed into a rectangular enclosure by bending on the other score lines 7 and 9. The endmost bottom flaps 30 and 31 are then folded 20 inwardly and the longitudinal flaps 28 and 29 are folded thereover with the locking tabs positioned so that the points thereof enter the wide portions of the slots 42 and 43. The tabs 39 bend on the scores 37 and 38 and slide under the inner faces of the end flaps until the scores 37 register with the slots. At this point the end portions of the offsets 40 enter the restricted ends 45 and 46 of the slots and the tabs are moved to their full 25 position under the end flaps with the inner face of the longitudinal flaps in contact with the outer face of the end flaps. When moving into this position the tongues 49 spring through the openings 59 and further enhance interlocking engagement between the flaps. This completes assembly of the bottom and the case may be turned 30 rights up for insertion of a liner 66 which may be formed of a single strip of the board-like material bent intermediate its ends on a score 67 to provide a mid rib 68 of double thickness extending from the top of the case to the bottom where the board is bent outwardly on scores 69 and 70 to provide bottoms 71 and 72 extending over the exposed portions of the locking tabs as shown in Fig. 2. The ends of the board are then bent on the scores 73 to provide end portions 74 engaging the inner faces of the ends of the case as shown in Fig. 3. The end portions 74 are provided with openings 75 registering with the handhold openings 36 in the ends of the case and the portions 55 36 forming the openings 75 are moved outwardly 50 through the handholds to overlap the outer faces of the ends of the case and form smooth rounding edges for the upper portions of the handholds and to retain the ends of the liner against the 60 ends of the case.

In order to support the mid rib in vertical position, the sides of the case may be provided with inwardly extending tongues 77 engaging between the plies of the mid rib as shown in Fig. 2.

65 The merchandise, for example, eggs, is packed within the compartments 78 and 79 formed on the respective sides of the mid rib up to substantially the level of the upper edges of the case walls. It is obvious that by reason of the shape 70 of the lock tabs and the stiff character of the board from which the case is constructed that the weight of the contents acting upon the bottoms of the compartments clamp the locking tabs to prevent the locking tabs from sliding out of the 75 slots. Consequently, the bottom flaps cannot

open up as long as the contents are in the case.

After insertion of the contents, the longitudinal side flaps 32 and 33 are turned inwardly over the top of the case and the end flaps 34 and 35 are folded thereover so that the corners of the lock tabs 53 and 54 pass through the wider portions of the slots 55 and 56 as shown in Fig. 4 to engage the skid tabs 62 which are then resting upon the contents of the case. The skid tabs 62 thus provide easy entrance of the corner lock tabs 53 and 55 and guide them into position as they are pushed through the slot-like openings 55 and 56 until the offset portions pass into gripping contact with the restricted ends of the slots 57 and 58. At this point the tongues 59 slip through the openings 60 in the lock tab and retain the offset portions of the lock tabs in the slots with the corner tabs extending under the side flaps.

The case is readily opened for inspection of the contents at any time by applying pressure under the end flaps 34 and 35 to effect withdrawal of the lock tabs 53 and 54 during which movement the retaining tongues 59 slide out of the openings 60 and permit release of the flaps. After inspection the closure flaps are returned to closed position and are secured by the interlocks as previously described.

After the contents have been removed from the case, the case is readily collapsed by withdrawing the liner and disengaging the interlocks of the top and bottom flaps, after which the sides are hinged on the scores 8 and 17 to flatten the case to permit stacking thereof with other cases for storage or shipment for reuse.

In Fig. 10 is illustrated a modified form of the invention in which the skid tab 62' is located relatively to the slot 56 so that the locking tab 53' may be turned retractively instead of being pushed forwardly as in the first described form of the invention.

While we have particularly described the invention in connection with a box or container having closures formed by both top and bottom flaps, it is obvious that the invention may be carried out in securing the bottom flaps of a removable lid type box as well as various portions of other types of stiff box structures.

It is also obvious that the tuck flap and skid tab of the present invention may be adapted to boxes or cartons having closures of various forms and that the position of the skid tab and lock flap may be arranged sideways or cornerways to accommodate them to the particular box structure.

What we claim and desire to secure by Letters Patent is:

1. In a stiff board case having overlapping flaps, one of said flaps having a bias arranged slot and provided with a tongue projecting into said slot, and the other flap having spaced scores extending diagonally across the corner of said other flap to provide a corner tab offset from the plane of said flap to facilitate passage through said slot and movement of said corner into contact with the underside of said flap having the slot and said offset portion into position contained in said slot, said offset portion having an opening for receiving said tongue.
- 15 2. In a stiff board case having overlapping flaps, one of said flaps having a bias arranged slot and provided with a tongue projecting into said slot, a skid tab formed from said flap and bent retractively across said slot on the side opposite the other of said flaps, and spaced scores extending diagonally across the corner of said other flap to provide a corner tab offset from the plane of said flap to facilitate movement of said corner into contact with the skid tab for guiding
- 20 25 the corner tab into contact with the underside of said flap having the slot and said offset portion into a position contained in said slot, said offset portion having an opening into which said tongue engages when the offset portion is in said slot.
- 30 3. In a stiff board case having overlapping flaps, one of said flaps having a slot-like opening and the other having a locking tab adapted to be projected through said opening and having an offset adapted to engage in said slot, said offset having an opening, and a projection extending into the slot-like opening for receiving said tongue.
- 35
